UNITED STATES PATENT OFFICE.

GEORGE A. KOHOUT, OF CHICAGO, ILLINOIS.

REAR-DUMP STOKER.

Application filed November 29, 1922. Serial No. 604,057.

My invention relates to stokers, and more particularly to the type of stoker shown in my Patent No. 1,855,095, patented Oct. 5, 1920.

- 5 It is a purpose of the invention to provide a hopper feed stoker operating on the general principles of the device shown in the above mentioned patent, that is, provided with members for accelerating the movement 10 of the fuel from the hopper to the stoker to deposit said fuel at the forward end of the stoker from which the same is moved toward the rear or discharge end by the operation of a single lever as described 15 in said patent. The member for accelerating the movement of fuel is preferably in the form of a pusher member which is provided with a refractory body portion and an inner face of refractory material.
- 20 It is a further purpose of the invention to provide a stoker of the above mentioned character, or of any other type wherein the fuel moves from a receiving to a discharge end thereof, with an ash dumping means 25 which is so constructed that the fuel will not be moved off the stoker into the ash pit when the ashes are being dumped.

It is more specifically a purpose of the invention to provide a dumping section, or ash 30 dumping member, which is provided with a member serving to act as a dam or partition to prevent the movement of the fuel off the end of the stoker when said ash dumping member is moved to dumping position.

35 It is still a further purpose of the invention to provide an ash dumping section of the character set forth above with means for preventing the fuel from moving off the end of the stoker when said ash dumping section 40 is out of its normal horizontal position whether above or below the normal position.

It is another purpose of the invention to provide means for preventing the movement of the stoker bars out of their position with 45 the top faces thereof in a plane when said ash dumping section is in dumping position. This is particularly important as a careless fireman may leave the stoker with the points of the sections extending upwardly into the fuel while cleaning out clinkers, if this means is not provided, thus damaging the stoker bars due to the heat of the fire burning off the points of the bars.

50 It is another purpose of the invention to provide a rear dumping section with clinker

removing means adapted to engage the rear wall of the furnace.

It is a further purpose of the invention to provide a dumping section of the character set forth above on a fuel feeding device of 60 any character whether the same be a stoker or a chain grate.

It is a further purpose of the invention to provide a stoker of the character shown in the above mentioned patent with a coal receiving section or bar that is of greater width than the other stoker bars making up the stoker so as to give the coal received on said receiving bar a greater throw than that given by the other sections of the 70 stoker, thus giving the fuel an initial acceleration aiding in moving the fuel along the same toward the discharge end thereof.

It has been found that in providing the means for preventing the fuel from moving 75 off the end of the stoker the same will also break up clinkers, and it is a purpose of the invention to provide means for breaking up the clinkers associated with said dumping bar forwardly thereof. In providing a 80 dumping section that can be moved upwardly above the horizontal position, the further advantage is obtained of knocking off and breaking up the clinkers at the bridge wall.

85 Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within 90 the scope of the claims.

95 In the drawings:

Fig. 1 is a view of a furnace partly in section showing the stoker and the associated parts in side elevation;

100 Fig. 2 is an enlarged view partly in section and partly in elevation showing the rear ash dumping section and associated parts in normal position;

Fig. 3 is a similar view showing the same 105 in ash dumping position;

Fig. 4 is a similar view showing the same in a raised position to clean clinkers off the bridge wall;

Fig. 5 is a somewhat diagrammatic view 110

showing the dumping device applied to a chain grate;

5 Fig. 6 is a similar view showing the dumping device applied to a stoker sloping downwardly toward opposite sides of the furnace from the middle thereof;

10 Fig. 7 is a similar view showing the dumping device applied to a stoker sloping toward the middle of the furnace;

15 Fig. 8 is a similar view showing the same applied to a stoker extending longitudinally of the furnace with the discharge at one end thereof and the fuel receiving end opposite thereto;

20 Fig. 9 is a view similar to Figs. 2, 3 and 4 of a slightly modified form of dumping section;

25 Fig. 10 is an end view of one of the closure and pusher members at the fuel receiving opening;

Fig. 11 is a longitudinal section thereof;

30 Fig. 12 is a transverse sectional view of a slightly modified form of closure and pusher block;

35 Fig. 13 is a longitudinal section thereof;

Fig. 14 is an inside end view of the pusher and closure member showing one application thereof;

40 Fig. 15 is a similar view of a different application thereof;

45 Fig. 16 is a similar view showing still another application thereof; and Fig. 17 is a fragmentary view similar to Fig. 3 of a modification.

50 Referring in detail to the drawings a furnace is shown in Fig. 1 having a bridge wall 20 and a front wall portion 21 between which the stoker 22 comprising the sections or stoker bars 23 is mounted. Said stoker bars are made as shown in detail in my Patent

55 No. 1,355,095 referred to above being connected together by means of the operating member 24 and being operated by means of the lever 25 through the link 26. The

60 first stoker bar 23', it will be seen from Fig. 1, is made of a much greater width across the top face thereof compared with the other stoker bars 23, but is of the same general construction and operates in the same man-

65 nner as the stoker bars 23 to throw the fuel toward the lower end of the stoker. This action takes place due to the construction of the bars set forth in detail in said patent which causes the same to have a throwing

70 action causing the fuel to be thrown from one bar or section to the adjacent bar or section toward the rear of the furnace as the lever 25 is actuated. The fuel is placed in the hopper 27 and will feed downwardly toward the stoker by the action of gravity but as such feeding is not to be absolutely relied on, and as it is desirable sometimes to feed the fuel at a more rapid rate than would be

75 done by gravity, the pusher members 28 are provided, which are adapted to travel along

the inclined surface 29 of the shelf-like portion at the forward end of the furnace up to the throat provided by the corner at 30 and the corner at 31 on the flat arch 32. When the members 28 move to a position adjacent said edges 30 and 31 the same will close the fuel feeding opening, thus serving as air sealing and closure members for the fuel feeding opening when not in operation, at such times also cutting off the fuel from the hopper and preventing the fire from burning back into the same. The members 28 thus serve to accelerate the movement of the fuel onto the stoker when actuated, and can also be used for cutting off the air through the fuel receiving opening and for closing the opening at the bottom of the hopper to prevent entrance of fuel into the furnace when this is desired. The members 28 are actuated by means of the handle 33 mounted on the shaft 34 and connected by the link mechanism 35 with the ears 36 on the member 28.

80 The member 28 is shown more in detail in Figs. 10 and 11. Said member comprises a metallic shell having the side walls 37, the top 38 and the bottom 39 and the outer wall 40. The top 38 extends rearwardly from the wall 40 and the ears 36 extend from said rearward extension of the top to the outer 85 end wall 40. Said ears are shown as being perforated in Fig. 11 so that the links 35 can be connected thereto.

85 In the form shown in Figs. 1, 10 and 11 the member 28 is filled with plastic refractory material 41 which is molded within the metallic casing so as to provide a refractory block having an outer metallic cover except on the face thereof toward the furnace or toward the inside of the fire box. While 90 refractory plastic material is shown in Figs. 1, 10 and 11, it will be evident that solid blocks of refractory material may be used as the material after being exposed to heat is substantially the same whether originally 95 in plastic form or originally in the form of a solid block.

95 In Figs. 12 and 13 a member 28' is shown having the ears 36' thereon within which the blocks 42 of refractory material are mounted, said blocks being held in place by means of the pins 43.

100 It will be seen upon reference to Figs. 1, 11 and 13 that the forward face of the block is inclined, this being due to the fact that the edge 30 and the edge 31 are not in exact vertical alignment. A plurality of the members 28 or 28' is used for closing the opening in the front of the furnace through which the fuel is fed, and for moving the same along the shelf-like portion onto the stoker.

105 In Figs. 14, 15 and 16 various ways of using said blocks are shown. In Fig. 14 the members 28 close the entire opening in

the front of the furnace, except for the spaces occupied by the metallic frames 44 for the doors 45 through which the operator may reach to clean out the clinkers without 5 removing the blocks 28. In Fig. 15 the blocks 28 are shown as extending all the distance from one of the side walls 46 to the other side wall 46 of the furnace. In Fig. 16 the blocks 28 are supplemented by 10 the blocks 28" which are of similar construction to the blocks 28 and are filled with refractory material 41", said blocks being adjacent the side walls 47 of the furnace and being removable to obtain access to the 15 sides of the fire box for the same purpose that the doors 45 serve.

An ash dumping section is provided at the discharge end of the stoker, said ash dumping section being shown in Fig. 2 in 20 its normal position prior to being dumped and comprising a dumping bar 48 pivoted at 49 on a fixed pivot mounted in any suitable manner in the setting of the furnace, said member 48 being provided with a depending ear 50 which has pivoted thereto at 51 the operating link 52, said link 52 being bent at an acute angle as shown at 53 at the end thereof that engages with the pivot 51. The member 52 as shown in Fig. 30 extends to the front of the furnace and through the front wall thereof, and is provided with a handle 54 for operating the same. In operation the handle 54 is pulled outwardly or pushed inwardly to move the 35 dumping section to the desired position. It will be evident that the ash dumping section 48 will move downwardly as the link 52 is moved to the right in Fig. 2 and upwardly when said link is moved to the left in Fig. 2. The member 48 is also provided with a perforated depending ear 55 to which the curved link 56 is pivoted at 57, said curved link being pivoted at the other end thereof to the ear 58 by means of the pivot 59. The ear 58 depends from the retarding 45 section 60 which serves as a dam or stop for the fuel to prevent the same from moving off the stoker and into the space left rearwardly of the member 60 when the ash 50 dumping section is moved to dumping position, said coal retarding or retaining member 60 being mounted on a fixed pivot at 61 and is provided with an arcuate rear end face 62 so that the same will pass by the 55 section 48 as the section 48 is moved to the position shown in Fig. 3.

It will be evident from Fig. 3 that when the bar 52 is actuated to move the member 48 to the dumping position as shown in said figure, the section 60 will be raised as shown in Fig. 3, this being due to the connection between said members 48 and 60, and the arrangement of the fixed and movable pivots thereof. It will be noted that the ear 58 is longer than the ear 55 and that ac-

cordingly the distance from the pivot 49 to the pivot 57 is less than the distance from the pivot 61 to the pivot 59. When the member 48 is dropped from its normal position the member 55 swings to the right, 70 thus carrying the lower end of the member 58 with it to the right due to the action of the link 56. As the distance between the pivots 57 and 59 is fixed and as the distance between the pivots 61 and 49 is fixed, 75 and as the members 55 and 58 extend in a vertical direction when the parts are in the position shown in Fig. 2, it will be evident that the movement of the member 55 to the right in Fig. 3 will move the member 80 58 to the right, which movement will cause a swinging of the member 60 about its pivot in a counter-clockwise direction thus raising the same to the position shown in Fig. 3. As the ear 58 is longer than the ear 55 the 85 movement of the member 60 will be less than the movement of the member 48. The link 56 is curved primarily to avoid engagement with the forward edge portion 63 of the member 48 when it swings into its 90 downward position as shown in Fig. 3. It is sometimes desirable to move the section 48 upwardly as shown in Fig. 4 above its normal position so as to break up clinkers, as a mere downward movement would leave 95 the clinkers fused together in a mass above the member 48, thus preventing cleaning of the fire as the clinkers would act as a support for the ash.

It is important that when the member 48 is raised, as well as when the same is lowered, that the coal does not move off the stoker into the ash pit, as there is a space existing between the member 48 and the stoker at such time. As the member 50 extends vertically and the member 58 also extends vertically, it will be evident that any substantial movement of the member 48 from a normal position will cause the pivot 57 to move to one side or the other of the 100 line from the pivot 49 to the pivot 59, thus drawing the ear 58 by means of the pivot 59 toward the right and again swinging the member 60 in a counter-clockwise direction so as to act as a stop or retainer 105 for the coal on the stoker. In operation the sections or stoker bars 23 move from the position shown in full lines in Figs. 3 and 4 to the position shown in Fig. 2 alternately to move the coal from the receiving to 110 the discharge end of the stoker, said bars being mounted on pivots 64 and having links 65 connecting with the links 66 for operating said members simultaneously by 115 means of the member 26.

It will be noted that the sections have sharp corners or points thereon at 67, and that when the sections are in the position shown in Fig. 2, said points 67 will project 120 up into the fuel bed. There will be a tend- 125

ency with the parts in such position for a considerable length of time for the points 67 to be damaged or burned off by the heat of the fire. A fireman will often in moving the 5 dumping section to dumping position attempt to remove clinkers from the rear of the stoker with a bar and will leave the stoker bars in the position shown in Fig. 2, unless means is provided for preventing such a 10 motion of the stoker bars when the dumping member is in dumping position.

It will be noted that the member 60 is provided with a concave portion 68 on the forward face thereof which is provided so 15 that the lip 69 which may be provided at the rear of the section 23 will clear the same to allow the stoker to be properly actuated when the parts are in the position shown in Fig. 2. There is, however, a rounded projection 70 provided on said member 60 which is at a greater distance from the pivot center of the member 60 than the concave surface 68, which projection 70 will extend into the path of the end portion 69 of the 20 member 23 when the member 60 is in a raised position as shown in Fig. 3, or when the member 48 is in dumped position. The edge 69 will then engage with the projection 70 so as to prevent movement of the stoker 25 bar 23, which being linked with the other bars through the members 65 and 66, will prevent movement of any of such bars to such a position that the points 67 thereof could be damaged. It is, of course, possible 30 to move the same very slightly as shown in dotted outline in Fig. 3 for a certain amount of play must be provided between the members 69 and 70, but this movement is so slight that the member 67 will not project into the 35 bed of the fuel so as to be damaged by the heat therein.

While the dumping section is shown as being applied to a stoker such as that shown in my patent referred to above in the views 45 described, yet it is evident that the same can be applied to many other types of stokers or fuel feeding devices. In Fig. 5 a chain grate 71 is shown operating over the sprockets 72, the discharge end thereof being at the 50 plate 73. The member 60' is connected with the dumping section 48' in the same manner in this construction as in that previously described, and the same is operated by any suitable means attached to the ear 50', said 55 members 60' and 48' being connected together by means of the link 56' connecting the ears 55' and 58'. In this form of the device a convexly curved forward edge 74 is provided on the member 60' in order to allow the same to move without interference 60 on the part of the member 73.

In Fig. 6 is shown a stoker that receives the fuel from a central fuel receiving member 75, said stoker comprising the inclined members 76, each of said members 76 lead-

ing to a discharge end, the discharge ends lying on the opposite sides of the device. A pair of dumping sections 48' is provided in this instance, one for each of the members 76 and said members are provided with the retainer or stop members 60' connected thereto in the same manner as described in connection with Fig. 5.

In Fig. 7 a different application of the dumping means is shown in which the stokers 77 are inclined toward each other at their discharge ends and the dumping sections 48' are arranged side by side, said sections being provided with the retainer or stop members 60' connected thereto in the same manner as 80 described in connection with Fig. 5.

In Fig. 8 a stoker 78 inclined in only one direction is shown which is provided with the dumping section 48' and the stop or retainer member 60' connected to the member 48' in the same manner as previously described. Quite often clinkers adhere to the bridge wall, and if desired the dumping section may be provided with means for removing the clinkers from the bridge wall. In Fig. 9 such a construction is shown, the bridge wall being indicated by the numeral 79 and the dumping section being designated by the numeral 80, said section being mounted on a fixed pivot 81 and having the portion 82 extending rearwardly of said pivot and having the convexly curved rear wall portion 83. Said section 80 is provided with an ear 84 to which the links 52'' and 55'' are connected in a similar manner to that in which the links 52 and 55 are connected with the section 48. It will be seen that as the dumping section 80 moves to dumping position the rearward extension 82 thereof will engage with the face 85 of the bridge wall 95 100 105 79, thus scraping any clinkers that may have adhered thereto off the same. By reciprocating said section 80 practically all said clinkers will be broken up and will drop into the ash pit. It is, of course, to be understood 110 that the section 80 is to be connected with a retainer or stop member similar to the section 60, by means of the links 55'.

In Fig. 17 a slight modification of the last stoker bar is shown. Said stoker bar 23' is similar to the bar 23 and the member 60 is mounted in the same way as in Fig. 3 and operates in the same way except that the projection 70 does not prevent movement of the stoker bars as it is not engaged by the lip 69' when the bar 23' is rocked on the pivot 64' but passes by the same.

Having thus described my invention, what I desire to claim and secure by U. S. Letters Patent is:

1. In a furnace the combination with a device comprising a plurality of members for receiving fuel thereon and moving said fuel from one end to the other thereof, of an ash dumping member at the discharge end of

said device, and means for holding the fuel from movement off the end of said device when said ash dumping member is moved out of normal position in any direction.

5. 2. In a furnace the combination with a stoker comprising a plurality of members for receiving fuel thereon and moving said fuel from one end to the other thereof, of an ash dumping member at the discharge end of 10 said stoker movable both upwardly and downwardly from its normal position, and means operatively connected with said dumping member to move into position for holding the fuel from movement off the end 15 of said stoker when said ash dumping member is moved out of normal position in either direction.

3. In a furnace, the combination with a device comprising a plurality of members 20 for receiving fuel thereon and moving said fuel from one end to the other thereof, of an ash dumping member pivotally mounted at the discharge end thereof and swingable downwardly from normal closing position to 25 ash dumping position, a fuel retaining member pivotally mounted between said dumping member and said device, and a link of fixed length pivoted directly to said members, the pivots of said link and said ash 30 dumping member being normally in alignment, the pivot of said link to said fuel retaining member moving upwardly when the pivots of the link and the pivot of the dumping member are moved out of alignment to 35 swing said fuel retaining member upwardly when said dumping member is swung downwardly.

4. The combination with a stoker comprising a plurality of stoker bars cooperating 40 to move fuel from the receiving end to the discharge end thereof, of an ash dumping member normally in a position to close the ash dumping opening at said discharge end, and movable in opposite directions from said 45 position, and a member operatively connected with said dumping member and interposed between said ash dumping member and said stoker for retaining the fuel on said 50 stoker when said dumping member is out of normal position in either direction.

5. In a furnace, the combination with a device comprising a plurality of members for receiving fuel thereon and moving said fuel from one end to the other thereof, of 55 an ash dumping member pivotally mounted at the discharge end thereof and swingable downwardly from normal closing position to ash dumping position, a fuel retaining member pivotally mounted between said dumping 60 member and said device, a rigid depending ear on each of said members and a link of fixed length directly pivoted to said ears so as to swing said fuel retaining member upwardly when said dumping member is swung 65 downwardly, one of said ears being longer

than the other thereof to normally throw the pivots of the links in alignment with the pivot of the dumping member.

6. The combination with a stoker comprising a plurality of stoker bars cooperating to move fuel from the receiving end to the discharge end thereof, of an ash dumping member normally having its upper surface flush with the upper surface of said stoker and movable above or below its normal position, a member interposed between said ash dumping member and said stoker normally flush therewith and means connecting the same with said ash dumping member whereby said interposed member moves upwardly into fuel retaining position when said ash dumping member is moved out of its normal position in either direction. 70

7. The combination with a stoker comprising a plurality of stoker bars cooperating to move fuel from the receiving end to the discharge end thereof, of an ash dumping member normally having its upper surface flush with the upper surface of said stoker, said ash dumping member being adapted to break up clinkers upon an upward movement thereof and to dump ashes upon a downward movement thereof, a member interposed between said ash dumping member and said stoker normally flush therewith and means connecting the same with said ash dumping member whereby said interposed member moves upwardly into fuel retaining position when said ash dumping member moves out of its normal position in either direction. 80

8. The combination with a stoker comprising a plurality of stoker bars cooperating to move fuel from the receiving end to the discharge end thereof, of an ash dumping member normally in a position to close the ash dumping opening at said discharge end, and means engaging one of said bars to hold said stoker bars against movement when said dumping member is in dumping position. 105

9. The combination with a stoker comprising a plurality of stoker bars cooperating to move fuel from the receiving end to the discharge end thereof, of an ash dumping member normally in a position to close the ash dumping opening at said discharge end, and means interposed between said dumping member and said stoker bars for holding said stoker bars against movement when said dumping member is moved to dumping position. 110

10. The combination with a stoker comprising a plurality of stoker bars connected together to move simultaneously cooperating to move fuel from the receiving end to the discharge end thereof, of an ash dumping member normally in a position to close the ash dumping opening at said discharge end, 120 125 130

and a member interposed between said ash dumping member and said stoker and connected with said dumping member so as to move to a position to retain the fuel on said stoker when said dumping member is out of normal position, said interposed member having means thereon engaging the adjacent stoker bar to hold the same from movement out of normal position when said interposed member is in fuel retaining position.

10 11. The combination with a stoker comprising a plurality of stoker bars each having a thick and a thin edge, said bars normally having their upper surfaces aligned and being linked together so as to move in unison, of an ash dumping member and a fuel retainer member interposed between said dumping member and said stoker bars and movable into and out of retaining position upon movement of said dumping member out of or into normal position, said retainer member having means thereon engaging the adjacent stoker bar to hold said

bars from movement out of normal position when said dumping member is out of normal 25 position.

12. The combination with a stoker comprising a plurality of stoker bars each having a thick and a thin edge, said bars normally having their upper surfaces aligned 30 and being linked together so as to move in unison, of an ash dumping member and a fuel retainer member interposed between said dumping member and said stoker bars and movable into and out of retaining position 35 upon movement of said dumping member out of or into normal position, said retainer member having means thereon engaging the adjacent stoker bar to prevent tilting of said bars to a position with the 40 thin edges thereof in the fuel bed, when said dumping member is out of normal position.

In witness whereof, I hereunto subscribe my name this 18th day of November A. D., 1922.

GEORGE A. KOHOUT.
